(57) **CLAIM**

We claim the ornamental design for a clamp head, as shown and described.

DESCRIPTION

FIG. 1 is a lower left front perspective view of a clamp head showing our new design;

FIG. 2 is an upper left rear perspective view thereof;

FIG. 3 is a front elevation view thereof;

FIG. 4 is a rear elevation view thereof;

FIG. 5 is a top plan view thereof;

FIG. 6 is a bottom plan thereof;

FIG. 7 is a left side elevation view thereof; and,

FIG. 8 is a right side elevation view thereof.

The broken lines shown represent unclaimed subject matter and form no part of the claimed design.
